UNITED STATES PATENT OFFICE

90,728

DESIGN FOR AN AMUSEMENT MACHINE
CABINET

Arthur B. Poinier and Martin J. Hanson, Oak
Park, Ill., assignors to Electra Corporation,
Chicago, Ill., a corporation of Illinois

Application March 31, 1933. Serial No. 47,658

Term of patent 3½ years

To all whom it may concern:

Be it known that we, ARTHUR B. POINIER and MARTIN J. HANSON, both citizens of the United States, residing at Oak Park, in the county of Cook and State of Illinois, have invented a new, original, and ornamental Design for an Amusement Machine Cabinet, of which the following is a specification, reference being had to the accompanying drawing, forming a part thereof, in which:

Figure 1 is a front view of the cabinet in perspective; and

Figure 2 is a top plan view of the same on a smaller scale.

We claim:

The ornamental design for an amusement machine cabinet, as shown.

ARTHUR B. POINIER.
MARTIN J. HANSON.
